UNITED STATES PATENT OFFICE.

JOSEPH S. DUNCAN, OF CHICAGO, ILLINOIS, ASSIGNOR TO ADDRESSOGRAPH COMPANY,
OF CHICAGO, ILLINOIS, A CORPORATION OF ILLINOIS.

PRINTING DEVICE.

1,080,201.

Specification of Letters Patent.

Patented Dec. 2, 1913.

Application filed March 23, 1912. Serial No. 685,811.

To all whom it may concern:

Be it known that I, JOSEPH S. DUNCAN, a citizen of the United States, residing at Chicago, in the county of Cook and State of Illinois, have invented certain new and useful Improvements in Printing Devices, of which the following is a specification.

This invention relates to that class of printing devices in which the printing characters are stamped in relief on one side of a metal plate, the other side of the plate showing the printing characters in intaglio.

One of the objects of this invention is to provide a printing device to print the address and salutation in a letter, the device being particularly adapted, although not so limited, for use in connection with a printing form constituting the subject matter of another application whereby an entire letter including the address and salutation may be printed from stamped up sheet-metal printing characters which make an impression closely resembling typewritten matter.

Another object of the invention is to provide a printing device on which the salutation is located adjacent the edge of the device so that the printed salutation will be spaced on the paper the requisite distance from the body of the letter.

A further object of the invention is to provide a novel construction at one edge of the device for the reception of index tabs so that the devices may be arranged in accordance with a card index system.

One preferred embodiment of my invention is illustrated in the accompanying drawings from which, when considered in connection with the following description, the invention will be readily understood.

On the drawings—Figure 1 is a plan view of a printing device embodying my invention and showing the printing side or that side on which the type characters appear in relief; Fig. 2 is a plan view showing the opposite side of the device on which the characters appear in intaglio; Fig. 3 is an end view of a stack of superimposed printing devices similar to that shown in Figs. 1 and 2; Fig. 4 is a side elevational view looking toward the left at the stack of devices shown in Fig. 3; Fig. 5 is a transverse sectional view taken substantially on the line 5—5 of Fig. 1; Fig. 6 is a similar view taken on the line 6—6 of Fig. 1; and Figs. 7, 8 and 9 are fragmentary views

showing modified forms of the rib at the lower edge of the device.

The device is preferably stamped from a single sheet of metal and comprises a body portion 11 which may be of any desired dimensions but is preferably large enough to accommodate a letter address and salutation. The type characters forming the address are preferably stamped up in relief in two or more lines 12 and the salutation 13 is stamped up in relief on the same side of the device but adjacent the lower edge thereof, the first letter of the salutation being preferably alined on the device with the first letter of the name to conform to the usual form of an ordinary typewritten letter. The metal at the lower edge of the device is preferably turned back upon itself as indicated by reference character 14 in Fig. 5 to produce a rib which serves the dual purpose of strengthening this edge of the device and spacing the devices apart when they are stacked, thereby protecting the printing surfaces of the stamped up printing characters. It is desirable that the salutation be stamped up very close to the edge of the device to obtain the requisite spacing between the salutation and the body of the letter and therefore the rib 14 is preferably omitted or cut away beneath that portion of the plate on which the salutation is formed to prevent injury of the salutation characters by the rib of an adjacent device when two or more devices are superimposed or stacked. This construction also enables the rib 14 to be formed before the salutation is struck up, thereby obviating any danger of injury to the printing characters of the salutation such as might occur if the rib 14 were rolled back in a machine after the salutation had been struck up and, furthermore, enables the printing devices to be made up in the factory and shipped out to customers who may themselves stamp up the address and salutation with an office graphotype or similar machine.

Adjacent the opposite margin of the device, or, in other words, above the address the metal is depressed below its normal plane to form a depressed panel 15 leaving the margin 16 in approximately its original plane. The metal extending beyond or outside the margin 16 is bent downwardly at 17 and then inwardly at 18 beneath the depressed panel 15, the lower face of the in-

- turned portion 18 lying substantially in a plane with the lower edge of the rib 14. The side walls of the depressed panel 16 are provided with alined perforations 19 and 20 and the downturned portion 17 is also provided with perforations 21 alined with the perforations 19 and 20 for the reception of suitable index tabs 22 which are inserted at the top of the device through the alined perforations. To lock the tabs against accidental displacement, slight projections 23 may be formed on the back of the device to engage in corresponding depressions 24 formed near the inner ends of the index tabs. From Fig. 3 it will be observed that the lower faces of the inturned ends 18 and the lower edges of the ribs 14 are spaced a slightly greater distance beneath the body of the device than the height of the struck up printing characters so that the devices are spaced apart thereby and the printing surfaces of the printing characters are protected from abrasion when the devices are stacked. The devices constructed as above described are intended to be stacked in a magazine in a printing machine and are fed therefrom endwise instead of sidewise as has been customary heretofore. In actual practice the devices are withdrawn from the bottom of the stack, one of the devices partially withdrawn being shown in Fig. 4.
- In Fig. 7 the lower edge of the metal blank is shown as folded back upon itself at 25, then depressed to form the rib 26, the edge being turned upwardly against the lower face of the body 11. In Fig. 8 the length of the turned back portion 25 is slightly increased and the edge beyond the rib 26 is disposed at substantially right angles with the body 11. In Fig. 9 the rib 27 is formed by rolling the metal back in substantially cylindrical form. Various other shapes in which the rib 14 may be formed will readily suggest themselves to those skilled in the art and it will be manifest that the present invention is not limited to any particular shape or configuration of rib.
- The printing devices are run through machines in which the address and salutation are printed upon letter paper in proper position so that the body of the letter may be printed below in close simulation of typewriting. In view of the comparatively soft metal necessarily employed in the construction of the printing devices it is desirable that they should be stiffened and strengthened to preserve their shape and this stiffening is effected in the present instance by the rib 14 at one edge of the device and the depressed panel 15 and bent portions 17 and 18 at the opposite edge. By omitting a portion of the rib 14 and stamping up the salutation very close to this edge of the de-

vice the proper spacing between the salutation and the body of the letter is secured. The impressions produced by the stamped up metal printing characters are a very close simulation of the typewriting which it is desired to imitate and will closely resemble the type impressions of a typewritten or imitation typewritten letter on which they may be made.

It is believed that my invention and many of its attendant advantages will be understood from the foregoing without further description and it will be obvious to those skilled in the art that the particular construction shown and described is capable of considerable modification without departing from the spirit of the invention or sacrificing any of the material advantages thereof.

I claim:

1. A sheet-metal printing device having an address stamped up in relief on one face thereof, a rib formed at one edge of the device and extending throughout a portion of its length, and a salutation stamped up in relief adjacent the said edge of the device and at the end of said rib.

2. A sheet-metal printing device provided with a salutation adjacent one edge stamped up from the body of the metal and having a rib extending along said edge from the salutation toward an end of the device.

3. A sheet-metal printing device provided with an address stamped up therein and a spacing rib at one edge thereof, said rib being omitted throughout a portion of the length of the device to permit the formation of a salutation in the device where the rib portion is omitted.

4. A sheet-metal printing device provided with a strengthening rib extending partially across the device at one edge thereof and having printing characters stamped up from the body of the metal at one end of said rib.

5. A sheet-metal printing device having an address stamped up in relief on one face thereof, the edge of said device below the address being turned back upon itself to form a rib extending partially throughout the length of the device, and a salutation stamped up in relief adjacent said edge of the device.

6. A sheet metal printing device provided with printing characters stamped up in relief on the front thereof, one edge of the device being turned over to form a rib on the back of the device, there being a depression in the front of the device adjacent the opposite edge thereof and forming an elevated panel on the back of the device, the edge portion of the device adjacent the panel being bent over upon the back of the device and overlapping the panel.

7. A sheet metal printing device having a depression in one face forming an elevated panel in the opposite face thereof, an edge

- portion of the device being folded back upon itself and overlapping the elevated face of the panel, the side walls of the panel being provided with registered openings.
- 5 8. A plurality of sheet-metal printing devices each having printing characters stamped up in relief on the upper face thereof and spacing means integral therewith to prevent engagement of the printing characters with adjacent plates when the latter are arranged one above the other in a stack, said means comprising a rib extending from one end partially throughout the length of the device, some of said printing characters being located adjacent said edge of the device between the other end of the device and the adjacent end of said rib whereby the lowermost device in a stack may be moved endwise from beneath the stack without the characters engaging the next above device in the stack.
- 10 9. A sheet metal printing device having a plurality of lines of type stamped up in relief on one face thereof, one line being disposed closely adjacent to one edge of the device, and a spacing element on the device in line with and at one end of said one line of type.
- 15 10. A sheet metal printing device having a plurality of printing characters stamped up from and projecting beyond one face thereof, said face being disposed in a plane common with the margins of the device and provided with a depressed portion beneath the plane of said face, and opposite walls of said depressed portion being provided with perforations adapted to receive an index tab.
